UNITED STATES PATENT OFFICE.

LEWIS C. MYERS, OF BROOKLYN, NEW YORK, ASSIGNOR, BY MESNE ASSIGNMENTS, TO
ROYAL TYPEWRITER COMPANY, INC., OF NEW YORK, N. Y., A CORPORATION OF
NEW YORK.

TYPE-WRITING MACHINE.

1,094,162.

Specification of Letters Patent. Patented Apr. 21, 1914.

Application filed June 14, 1909. Serial No. 501,902.

To all whom it may concern:

Be it known that I, LEWIS C. MYERS, a citizen of the United States, residing at Brooklyn, county of Kings, State of New York, have invented certain Improvements in Type-Writing Machines, of which the following is a specification.

This invention relates particularly to escapement devices of a typewriting machine. In the accompanying drawings: Figure 1 is a detail elevation partly in section of the escapement devices and means for operating them; Fig. 2, a detached sectional view showing the escape wheel shaft and the escape wheel secured thereto; Fig. 3, a detail edge view of one of the escapement dogs; Fig. 4, a detail side elevation of the toothed sleeve turning on the escape wheel shaft and having a gear adapted to intermesh with the carriage rack and a toothed wheel to be connected by drive pawls with the escape wheel; Fig. 5, an elevation looking at the left hand end of Fig. 4; Fig. 6, a detail view showing the adjustable back check cooperating with the escape wheel; Fig. 7, a side elevation of Fig. 6; Fig. 8, a detail view showing the loose escapement pawl with a rounded working face as having been set forward in position to give "drop"; Fig. 9, a similar view showing in full lines the position of the parts when the loose pawl moved by the stress of the escape wheel has been arrested by its limiting stop; Fig. 10, a front view of the escape devices; Fig. 11, a rear view thereof; Fig. 12, a detail view showing the escapement rocker as it may be operated in the Royal Standard machine; Fig. 13, a perspective view illustrating the space bar and its escapement actuating devices; Figs. 14 and 15 are detail views illustrating means for coupling the side levers of the space bar with their escapement actuating shaft; Fig. 16, indicates carriage shift devices; and Fig. 17 is a detail elevation of one of the coupling clips shown in Figs. 14 and 15.

The shifting carriage 1 carries two standards formed with concentric circular hubs, 2 and 3. The one 3 is threaded to receive a screw plug 4, the front or inner face of which is formed with a cup-shaped ball race 5. The rear face of the hub 2 of the other standard is recessed to form a cup-shaped ball race 6. An escape wheel 7 is secured to the shaft by a screw thread 8 adjacent

the rear end of the shaft; and on the ends of the shaft are tapered heads 10 and 11, forming the opposite parts of the respective ball races. In both races, 9 indicates the bearing balls. The head 11 has a tapered bore and is driven on to the tapered end 12 of the escape wheel shaft 12. The ball bearings are adjusted or set up by the screw plug 4. The tapered head 10 may be driven upon the end of the shaft 12, screwed thereon, or secured by a key-way; or, be integrally formed with the shaft 12, the latter being the preferred construction. Between the escape wheel 7 and bearing head 11 there is loosely mounted on the shaft, the sleeve 13 (Figs. 1, 4 and 5) formed at one end with a gear or ratchet 14 connected to the escape wheel by the spring pressed driving pawls 15, 15, (Fig. 10) that act to lock the parts together when rotated in one direction but permit free turning of the gear or ratchet wheel 14 in the other direction. The other or front end of the sleeve 13 is formed with a gear or ratchet 16 that engages the feed rack 17 of the machine.

The escapement rocker 18 is of a construction usual or well known. As shown in this drawing, the rigid dog is composed of a roller 19, the axis of which is disposed in a direction approximately radial to the axis of the escape wheel and the teeth of the wheel contact with the periphery of the roll. The loose dog 20 has a working surface that is rounded in the direction of the lengths of the dog as indicated at 21 in Figs. 8 and 9. The purpose of this rounding of the dog is to afford a minimum area of contact between its rounded surface and the teeth of the escape wheel and to facilitate the disengagement of the dog from the teeth. The ordinary back check stop 22 acting on the escape wheel is shown in Figs. 6 and 7. It is mounted upon a plate 23 rigid with the main frame or forming part of the shifting carriage frame and may be adjusted by an eccentric bolt 24 to the threaded end of which a lock nut 25 is applied.

The escapement rocker carrying the fast and loose dogs 19 and 20 may be actuated in any way desired. Thus, as shown in Fig. 12, the universal bar 26 is carried in the ends of hangers 27 carried on or by a shaft 28. When a finger key is depressed, the universal bar moves forward and contacts with an adjustable screw 29, in the tail or

end of the rocker plate that extends below its pivots 30. Such arrangement of the universal bar is similar to that employed in the Royal Standard push pin machines.

5 Fig. 1, shows a key lever construction in which 31 indicates one of the key levers adapted to act upon the universal bar 32 that is carried in the arms 33 rocking about an axis 34. There may be three such arms 10 33 one at each side of the machine and a central or intermediate one. Adjustably mounted on the central one of these arms is an upright 35 forked at its upper end, one of the ends 36 being adapted to contact with 15 a pin 37 in the side of an escapement actuating rod 40 and the other of which carries a headed pin 38 on which is guided the slotted end of the rod. This rod is pivoted by bolt 41 in the end of a plate 42, disposed between the jaws of the bifurcated lower end of the escapement rocker which are drawn together, to adjustably clamp the plate by a screw bolt 44. A projection 45 from the upper edge of plate 42 has attached to it one end of a coiled spring 46 whose other end is applied to the limber or pivoted dog of the escapement. The rear end of plate 42 has a right angle lug 47 tapped to receive a screw bolt 48 whose 20 front end bears against escapement rocker. This is to aid in the accurate adjustment of plate 42 in the rocker.

Fig. 13 shows the spacing devices. There is the usual space bar 45 located at the 35 front of the key-board and from it extend rearwardly side arms or bars 46, 46, having in their rear ends concentric pivot bearings 47, 47, adapted to receive a transverse bearing rod which may be the same rod 48 as 40 that upon which the key levers 31 are pivoted. In front of the bearing 48, the side arms 46 of the base bar are connected by a transverse rod 49 seated in slots in the under edges of the arms 46 and held up by 45 clips 50 having slots embracing the flattened ends of the rod 49 and secured by nuts 52 applied to the threaded ends of the rod. Instead of flattening the ends of the rods 49 and forming slots 51 in the clips, 50 the latter may have circular apertures as in Fig. 17 and the ends of the rod be circular. At or about the central part of the transverse rod 49 is adjustably secured an upright 53 adapted to engage the pin 37 on 55 the side of the escapement actuating rod when the space bar is depressed.

The carriage shift devices indicated in Fig. 16 are familiar or will be readily understood by those skilled in this art and 60 specific reference thereto seems unnecessary.

One of the purposes of adjusting the escapement wheel back check 22 is to permit the escape wheel to take different positions according to the desired "drop" from the 65 limber to the rigid dog. The rounding of

the working face of the limber dog compensates for this adjustment in the drop. Heretofore it has been the practice to make the engaging face of the limber dog straight in lines radial, or approximately so, to the 70 axis of the escape wheel and any change in position of the escape wheel teeth due to an adjustment to vary the "drop" will cause the edges or points of the teeth to engage the dog so that ultimately the face of 75 the latter will become scored or worn. By rounding the working face of the limber dog, however, it always presents a rounded face to the teeth of the escape wheel whatever may be the adjustment with respect to 80 drop; and whatever such adjustment may be the round surface of the dog is engaged by the flat faces of the teeth of the escape wheel and not by the corner or edge thereof. The drawings show a special form of 85 under cut teeth designed to afford clearance where an extreme "drop" is employed and also on the forward motion of the escapement dog.

I claim:

1. Typewriting machine escapement mechanism comprising a toothed escape wheel and a coöperating loose dog movable transversely to the plane of the wheel in and out between its teeth and having its working 90 face rounded in the direction of its length and of the length of the teeth.

2. Typewriting machine mechanism comprising an escape wheel shaft, an escape wheel fast thereon, a sleeve turning loosely 100 on the shaft and having two ratchet wheels, a feed rack with which one of the wheels engages, a locking pawl connecting the other ratchet and the escape wheel for rotation together in one direction only, ball bearings applied to the ends of the shaft respectively outside of the escape wheel and the ratchet 105 engaging the feed rack.

3. Typewriting machine escapement mechanism comprising an escape wheel shaft and 110 an escape wheel fast thereon, a ratchet, means for connecting the ratchet and escape wheel for rotation together in one direction only; a second ratchet rotating in either direction with the first one, a feed rack with 115 which the latter ratchet wheel engages, ball races at the respective ends of the shaft composed of stationary parts and conical plugs applied to the ends of the escape wheel shaft.

4. Typewriting machine escapement mechanism comprising an escape wheel shaft having a tapered end and a head driven thereon and adapted to form one member of a ball race, and a head on the other end of the shaft adapted to form one member of 125 another ball race.

5. Typewriting machine escapement mechanism comprising standards in one of which is fitted an adjustable screw plug, the inner 130

end of which forms one member of a ball race and in the other of which is formed one member of another ball race, an escape wheel shaft having at its respective ends 5 heads constituting the other members of the respective ball races, and located between said heads, an escape wheel fast on the shaft, a sleeve having two ratchets with one of which the escape wheel is locked for rotation in one direction only and the other of which engages the feed rack of the machine.

6. Typewriting machine escapement mechanism comprising an escape wheel shaft, an escape wheel fast thereon, fast and loose 15 escapement dogs coöoperating with the wheel and an adjustable back stop pivoted upon an adjustable eccentric bolt.

7. Typewriting machine escapement mechanism comprising a space bar, side arms 20 thereof rocking about an axis at their rear ends, a transverse shaft seated in jaws in the side arms in front of their pivot, clips connecting the side arms and transverse shaft and clamp nuts for rigidly uniting

them, and an arm extending from the transverse shaft and adapted to operate the escapement devices of the machine. 25

8. Escapement mechanism for a writing machine, comprising an escapement rocker, a plate adjustably clamped in the lower end 30 thereof, an operating rod pivoted to the plate and a gage screw turning in the rear end of the plate and bearing against the rocker.

9. Escapement mechanism comprising an 35 escape wheel shaft tapered at one end, having an integral head at the other end and a screw head contiguous the head, an escape wheel screwed upon said thread, and a separately formed apertured head fitting the 40 tapered end of the shaft and secured thereon by pressure.

In testimony whereof, I have hereunto subscribed my name.
